UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

JACQUARD INDICATOR FOR DROP-BOX LOOMS.

Application filed April 19, 1923. Serial No. 633,130.

To all whom it may concern:

Be it known that I, EPPA H. RYON, a citizen of the United States, residing at Waltham, in the county of Middlesex and State 5 of Massachusetts, have invented a new and useful Jacquard Indicator for Drop-Box Looms, of which the following is a specification.

This invention relates to a drop box loom 10 having a jacquard mechanism associated therewith and connected to indicate and control the movements of the drop boxes. Jacquard indicators have been heretofore known and used in which the indication by 15 the jacquard was transmitted directly to the drop box controlling mechanism, and in which the parts were consequently entirely dependent for their time relation upon the movements of the jacquard lifter bars. It 20 has been found in operation that this particular time relation is not well adapted to the operative movements of the drop box mechanism and much difficulty has arisen on this account.

25 It is the object of my present invention to provide a jacquard indicator so constructed that the indication from the jacquard will be transferred to the drop box mechanism by separately actuated devices which may be 30 caused to operate in any desired time relation to the movements of the drop boxes. To the accomplishment of this object, I provide an actuating member connected to the loom driving mechanism, and indicating devices operated thereby but movable to operative or inoperative position by the jacquard mechanism.

35 My invention further relates to arrangements and combinations of parts which will be hereinafter described and more particularly pointed out in the appended claims.

A preferred form of my invention is shown in the drawings in which—

Fig. 1 is an end elevation of certain parts 40 of a drop box loom embodying my improvements;

Fig. 2 is a plan view of my improved indicator;

Fig. 3 is a side elevation thereof;

Fig. 4 is a sectional plan view, taken along the line 4—4 in Fig. 3; and

Fig. 5 is a detail elevation showing certain parts in a different position.

Referring to the drawings, I have shown 55 a loom side 10, a drop box lifter rod 11, a

floating lever 12 connected to said rod, and links 13 connecting the lever 12 to a pair of bell cranks 14 and 15 mounted on a fixed pivot 16. The bell cranks 14 and 15 are connected by links 17 to mutilated 60 vibrator gears 18 mounted upon arms 19 pivoted at 20 to the loom side 10. A link 21 connects the free end of each arm 19 to a controlling device or indicating lever 22 pivoted at 23 on a stand or bracket 24 65 adapted to be bolted to the upper part of the loom side 10.

As a selected gear 18 is raised or lowered by its link 21, it will be engaged by one or the other of the mutilated cylinder or driving gears 25 and 26 and will thus be given a half revolution in one direction from the other, changing the position of its associated link 17 and bell crank 14 or 15. A latch 190 (Fig. 1) is provided for locking the vibrator lever 19 in raised or lowered position. This latch is positively moved rearward to unlock the vibrator lever by a cam 191 fixed to rotate with the cylinder gear 25 and a spring 192 is provided for 70 yieldingly moving the latch to locking position. The parts thus far described are or may be of the usual type and in themselves form no part of my present invention, which relates particularly to the mechanism provided for moving the indicating levers 22. 75

Each controlling device or indicating lever 22 is positioned by a lug or projection 28 on the upwardly extending arm of a three-armed rocking lever or positioning 80 member 29 loosely mounted on a fixed pivot 30. The lug or projection 28 on the lever 29 engages a cam surface of the lever 22 and movement of the lever 29 from one to the other of the two positions indicated in Fig. 90 3 causes the corresponding indicating lever 22 to be raised or lowered. The lever 22 has such engagement with the rocking lever 29 that the lever is held yieldingly in one or the other of its two extreme positions. 95

The two horizontally disposed arms of each rocking lever 29 are provided with upwardly extending connections or indicating fingers 31, each provided with a hook-like projection 32. The upper ends of the fingers 100 31 are received in recesses 33 formed in the sides of sliding bars or pattern controlled members 34. One end of each bar 34 is provided with a straight slot 35 through which extends a fixed stud 36. The other 105

end of each bar 34 has a curved or cam slot 37 through which a stud 38 extends.

Cords 39 and 40 extend from the opposite ends of each slide 34 through guides or bushing in guide arms 41, thence upwardly to the lifter wires 42 of a jacquard mechanism not shown in detail.

The slides 34, cords 39 and 40, wires 42, lifter bars 50 and the other parts of the 10 jacquard mechanism as a whole constitute pattern controlled mechanism for rendering the actuator 43 operative to move a selected-controlling device or indicating lever 22.

An actuator or actuating lever 43 (Fig. 15) 3 is pivoted at 44 on the bracket 24 and is connected by a link 45 to suitable driving mechanism such as a cam 46 mounted to rotate with a driving shaft 47. A projection 48 extends laterally from the lever 43 in 20 position to engage the hooks 32 of the indicating fingers 31. The lever 43 is regularly raised and lowered by the loom driving mechanism and upon each upward movement engages such of the fingers 31 as have 25 been moved into the path of the projection 48. When one of the fingers is thus engaged, its corresponding lever 29 will be rocked as the finger is raised, changing the position of the associated lever 22 and raising or lowering its link 21, arm 19 and gear 18.

Having thus described the construction of my improved indicator, the operation thereof will be readily understood. Whenever 35 one of the lifter wires 42 is engaged by a jacquard lifter bar 50, the wire 42 will be raised, moving the associated cord 39 or 40 and thus shifting the corresponding sliding bar 34 in one direction or the other. The 40 use of the cam slots 37 prevents accidental displacement of the bars 34. As each bar 34 is moved in one direction or the other, one of its indicating fingers 31 will be moved into the path of the projection 48 and will 45 remain in such position until it is engaged by the projection on the next upward movement thereof.

This upward movement of the actuator 43 and projection 48, however, need have no 50 particular time relation to the time of movement of the bar 34 but should be in timed relation to the movement of the cam 191 which releases the vibrator levers 19. This movement of the actuator 43 may be at any 55 time subsequent to the operation of the jacquard and the movement of the bar 34. When one of the fingers 31 is thus raised, it will reverse the position of its rocking lever 29, raising or lowering the corresponding 60 indicating lever 22 and calling a change in the position of the drop boxes.

I have thus provided a very simple and reliable mechanism which avoids the necessity of moving the indicating levers 22 in a definite and restricted time relation to the move-

ments of the lifter bars 50 of the jacquard and the indicating levers are free for movement in any desired relation to the operation of the drop box mechanism.

Having thus described my invention and 70 the advantages thereof, I do not wish to be limited to the details herein disclosed otherwise than as set forth in the claims, but what I claim is:

1. In a drop box loom, in combination, 75 drop box actuating mechanism, a plurality of controlling devices therefor, a single actuator for said controlling devices regularly moved by said loom, driving mechanism therefor, and additional pattern-controlled 80 means including a jacquard mechanism effective to render said single operating member operable or inoperable with reference to a selected controlling device.

2. In a drop box loom, in combination, 85 loom driving mechanism, a plurality of drop boxes, lifting mechanism therefor, and means to render said lifting mechanism effective to produce a selected box movement, 90 said means including a regularly moved actuator operatively connected to the loom driving mechanism, devices connected to control the operation of said lifting mechanism, 95 positioning members for said controlling devices, a plurality of connections between said positioning members and said actuator, and additional pattern-controlled means including a jacquard mechanism effective to render a selected connection operative.

3. In a drop box loom, in combination, 100 loom driving mechanism, a plurality of drop boxes, lifting mechanism therefor, and means to render said lifting mechanism effective to produce a selected box movement, 105 said means including an actuator operatively connected to the loom driving mechanism, indicating levers connected to control the operation of the lifting mechanism, rocking levers positioning said indicating levers, a pair of connections between each rocking 110 lever and said actuator, and pattern-controlled means to render a selected connection operative.

4. In a drop box loom, in combination, a 115 plurality of drop boxes, actuating mechanism therefor, a plurality of indicating levers controlling the operation thereof, a regularly moved actuator for said indicating levers, and additional pattern-controlled 120 mechanism including a jacquard mechanism effective to render said actuator operative to move a selected indicating lever.

5. In a drop box loom, in combination, a 125 plurality of drop boxes, actuating mechanism therefor, a plurality of indicating levers controlling the operation thereof, a rocking lever for each indicating lever, a pair of hooked indicating fingers mounted on each rocking lever, a regularly moved actuator positioned adjacent said fingers, a 130

jacquard mechanism, and connections from said jacquard mechanism to said fingers by which a selected finger may be moved to place its hook in the path of said actuator.

5 6. In a drop box loom, in combination, a plurality of drop boxes, actuating mechanism therefor, a plurality of indicating levers controlling the operation thereof, a rocking lever for each lever, a pair of indicating fingers mounted on each rocking lever, a regularly moved actuator positioned adjacent said fingers, a sliding bar for each pair of indicating fingers, said bar having notches to receive the ends of said fingers, 10 13 a jacquard mechanism, and connections from said jacquard mechanism to said sliding bars whereby a selected bar may be moved in a desired direction to operatively position one of the fingers associated therewith.

20 7. In a drop box loom, in combination, a plurality of drop boxes, lifting mechanism therefor, a plurality of indicating levers controlling the operation thereof, a rocking lever for each lever, a pair of indicating fingers mounted on each rocking lever, a regularly moved actuator positioned adjacent said fingers, a sliding bar for each pair of indicating fingers, said bar having notches 25 to receive the ends of said fingers, a jacquard mechanism, connections from said jacquard mechanism to said sliding bars whereby a selected bar may be moved in a desired direction to operatively position one 30 of the fingers associated therewith, and means to hold said bars yieldingly in either extreme position.

35 8. In combination, supporting means, going means including the reciprocating 40 shed-forming element of a loom and a pair of moving actuators moving in relatively opposite directions, mechanism to be driven engaged with one of the actuators, carrier means for said mechanism shiftable to move the latter into engagement with the other actuator, said going means also including a third moving actuator from which to cause 45 shifting of the carrier means, motion transmitting means for transmitting shifting motion from the third actuator to the carrier means having a coupling connectible with one of them, means to control said coupling including another coupling movable into and out of the path of movement of said 50 element and adapted to be moved thereby when the latter moves in one direction, and pattern-controlled means for controlling the movement of the latter coupling.

55 9. In combination, supporting means, going means including the reciprocating shed-forming element of a loom and a pair of moving actuators moving in relatively opposite directions, mechanism to be driven engaged with one of the actuators and normally urged into engagement with the other 60

of them, carrier means for said mechanism movable therewith, a detent opposing movement of the carrier means and consequently of said mechanism and movable to clear the carrier means, said going means also including a third moving actuator, means to transmit movement from the third actuator to said detent having a coupling connectible with one of them, means to control said coupling including another coupling movable into and out of the path of movement of said element and adapted to be moved thereby when the latter moves in one direction, and pattern-controlled means for controlling the movement of the latter coupling. 70 75 80

10 10. In combination, supporting means, going means including the reciprocating shed-forming element of a loom and a pair of moving actuators moving in relatively opposite directions, mechanism to be driven normally held in position of engagement with one of said actuators, carrier means for said mechanism shiftable to move the latter into engagement with the other actuator, a cam engaged by the carrier means and movable to two different positions, one to cause shifting of said mechanism and the other to release the same, said going means also including a third moving actuator, separate means to shift the cam to said positions, respectively, each including a coupling connectible with the third actuator, separate means respectively controlling said couplings and each including another coupling movable into and out of the path of movement of said element and adapted to be moved thereby when the latter moves in one direction, and pattern-controlled means for controlling the movement of the latter couplings. 90 95 100

11. A drop box actuating and controlling mechanism having, in combination, a frame, a pair of cylinder gears mounted in said frame and rotated in opposite directions, drop box actuating mechanism, vibrator gears connected thereto, vibrator levers for said vibrator gears, movable to cause said gears to engage with either one of said cylinder gears, an actuator having regular actuating movements, means to connect said actuator to raise or lower a selected vibrator gear, said latter means including actuator-engaged controlling elements, and means to select and move one of said controlling elements into the path of said actuator, said selective means including a jacquard mechanism having lifter bars, lifter wires connected to said controlling elements, and pattern-controlled means effective to move selected wires into and out of position for engagement with said lifter bars. 110 115 120 125

12. A drop box actuating and controlling mechanism as set forth in claim 11, in which a latch is provided for each vibrator lever, together with means to move said latch into and out of locking position, and in which 130

4
the release and movement of each vibrator is subsequent to the indication of its movement by said jacquard mechanism.

13. A drop box actuating and controlling mechanism as set forth in claim 11, in which the means for selectively moving the controlling elements includes a positioning member movable to different operative positions, said positioning member being effec-

tive to move said controlling elements into 10 and out of the path of said actuator and in which certain jacquard lifter wires are connected to selectively move said positioning member as indicated by the jacquard pattern.

15
In testimony whereof I have hereunto affixed my signature.

EPPA H. RYON.
